UNITED STATES PATENT OFFICE.

CHARLES L. RAYFIELD, OF CHICAGO, ILLINOIS, ASSIGNOR TO RAYFIELD MANUFACTURING COMPANY, A CORPORATION OF ILLINOIS.

OIL-PUMP CONSTRUCTION.

Application filed November 5, 1927. Serial No. 231,184.

My invention relates to pumps, and more particularly to a rotary pump of that type wherein a pivotally mounted ring member is actuated by an eccentric to force the fluid 5 from the pump.

It has been the practice heretofore in a rotary pump of the above character to provide a link connection for the ring member of the pump adapted to prevent this member from rotating with the eccentric disposed therein and also adapted to permit of the ring member having an oscillatory motion. I have found that this link construction is not only relatively expensive to make, but 15 also involves expensive machining operations in order to properly fit it to the cylinder of the pump, as well as to the oscillatory ring member. Then, too, this construction is not very satisfactory for the reason that 20 it is exposed to considerable wear, and hence is detrimental to the efficiency and longevity of the pump.

It is, therefore, the object of my invention to provide an improved rotary pump, 25 wherein the above mentioned linkage is eliminated and a novel and inexpensive pivotal mounting is provided for the ring member actuated by the eccentric.

Another object of the invention is to provide a relatively simple and inexpensive rotary pump construction capable of handling 30 small quantities of fluid with relatively high efficiency, and especially adapted for use in connection with the pumping of fuel for 35 oil burners or the like.

In accordance with the general features of the present invention, I provide a rotary pump including a cylinder having inlet and outlet passageways, a rotary eccentric member 40 disposed in the cylinder, a ring or pressure member fitted on the eccentric and adapted to be oscillated thereby, and a pin anchored in the cylinder and extending through an opening in the edge of the ring member, the 45 ring member being adapted to pivot about the pin to force liquid from the inlet passageway into the outlet passageway. This pin construction is of a very simple and inexpensive nature and not only serves as a 50 mounting for the ring member, but also serves as a barrier between the inlet and outlet passageways to prevent leakage there-

Other objects and advantages of my invention will more fully appear from the 55 following detailed description taken in connection with the accompanying drawing, which illustrates a single embodiment thereof and in which:

Figure 1 is a fragmentary vertical sectional 60 view through the rotary pump of my invention;

Figure 2 is a cross-sectional view taken on substantially the line II-II of Figure 1 looking in the direction indicated by the arrows; 65

Figure 3 is a cross-sectional view taken on substantially the line III-III of Figure 1 looking in the direction indicated by the arrows and showing the neutral positions of the eccentric and ring member of the pump 70 drawn to a reduced scale;

Figure 4 is a view similar to Figure 3 showing the positions of the eccentric and ring member during the charging of the pump with fluid, and 75

Figure 5 is a view similar to Figure 3 showing the positions of the eccentric and ring member during the discharge stroke of the pump.

In the drawings: 80
Like reference characters designate similar parts throughout the several views.

The reference character 10 designates generally a pump block which includes an annular end member or plate 11. Extending 85 through the block 10 is a shaft 12 which may be actuated by any suitable source of power. This shaft extends through a bore 13 of a larger diameter than that of the shaft. Disposed in the bore 13 and surrounding the 90 shaft 12 is a packing 14 which is held in place by means of a bearing box 15 and a packing box 16. It will be noted that an end of the shaft 12 projects outwardly beyond the annular member 11.

Surrounding the shaft 12 and positioned flush with the end member or plate 11 is a flat member 18 which comprises the cylinder of the pump. The cylinder 18 is secured to the plate or member 11 by an end plate 20 through the means of bolts 19 which extend through the plate 20, the cylinder 18, and to the member 11. The end plate 20 has formed integral with it a central hollow boss 21 in which the associated extreme end of shaft 12 105 is journaled.

The cylinder 18 has a central or concentric opening 22 which defines the pump chamber. Disposed within this opening 22 is what I term a ring member 23 which has a diameter 5 slightly less than the diameter of the opening 22. Rotatably fitted in the ring member 23 is an eccentric member 24 which is secured to shaft 12 by means of a woodruff key 25.

The ring member 23 has formed in its periphery 10 a groove 26 through which extends a fixed pin 28. The pin 28 is of such a diameter that it is adapted to fill up substantially the entire groove 26, but yet at the same time permit of a pivotal movement of the ring member 23. One end of this pin 28, as best shown in Figure 1, is tightly fitted in an opening 29 in end member 11 of the pump block 10. The other end of the pin 28 is tightly fitted in an opening 30 formed in end 15 plate 20. This pin 28 is tightly held in these two openings 29 and 30 against movement. Moreover, it will be noted that the end plate is properly aligned with end member 11 through the means of dowel pins 30'.

25 The ring member 23 also has formed in it a pair of oil openings 31 and 32, one being disposed on each side of groove 26. These oil openings permit of some of the oil being pumped reaching the eccentric 24, whereby 30 the pump is self-lubricating. Of course, it is to be understood that my novel pump may be used to pump other fluids besides oil without deviating from the features of my invention. Obviously if it is used to pump another 35 fluid, the openings 31 and 32 should be omitted.

The pump block 10 has formed integral with it a pair of lateral extensions 33 and 34, in each of which is a threaded opening 35—36. 40 The opening 35 comprises the inlet of the pump, and the opening 36 comprises the outlet of the pump. Suitable pipelines (not shown) may be threaded into these openings 35 and 36. The inlet 35 is disposed in communication with a passageway 37 (Figure 2) formed in the block 10. This passageway is closed off at its lower end by a plug 38 threaded therein. The upper end of the passageway 37 intersects an opening 40 which extends clear through the plate 11. It will, of course, be understood that when the ring 23 is in either the position shown in Figures 3 or 5, the opening 40 will be disconnected from the pump chamber or opening 22.

55 The opening 36 is disposed in communication with a passageway 42 which has a closure plug 43' threaded into its lower end. The upper end of the passageway 42 communicates with an opening 43 which also extends clear through the member 11 and has its outer 60 end in register with the pump chamber or opening 22. The opening 43 has an enlarged portion 41 (Figure 3) which communicates with the annular opening 22 in the cylinder 18. 65 Of course, it must be noted that when the ring

23 is in the position shown in Figure 3, this opening 43 is disconnected from chamber 22.

Attention is directed to the fact that I purposely make the outlet opening 43 substantially larger than the inlet opening 40 for the reason that I find that when the pump is operating at a relatively high speed this arrangement tends to obviate the socalled "crack" of the pump and also enables the pump to operate smoothly.

75 Attention is also directed to the fact that the outer end of the bearing box 15 is disposed substantially flush with the outer surface of member or plate 11. This box is held against rotation by means of a setscrew 45 threaded 80 into the block 10, as shown in Figure 1.

The operation of my novel rotary pump will now be briefly discussed in connection with Figures 3, 4 and 5, which illustrate the various phases of the operation of the pump. 85 When the eccentric 24 is in the position shown in Figure 3, it causes the ring member 23 to assume a position wherein the pin 28 is disposed entirely within the groove or slot 26, thus resulting in both of the openings 40 and 43 being disconnected from the chamber or opening 22. The rotation of the shaft 12 in a clockwise direction will result in the eccentric 24 traveling from the position shown in Figure 3 to the position shown in Figure 5. 90 When the ring member 22 is in this position, it will have been moved out of register with opening 40, whereby this opening is disposed in communication with the pump chamber 22. Obviously this movement of the eccentric 24 will result in fluid being drawn into the pump 95 through the opening 40 from the inlet 35. Continued rotation of the eccentric 24 will cause it to assume the position shown in Figure 4, wherein the chamber 22 is connected through the opening 43 with the outlet 36, thus allowing the fluid to be forced from the pump chamber. Thereafter the eccentric 24 travels through the two positions shown and described in connection with Figures 3 and 4, thus resulting in the entry of a fresh batch 100 of liquid into the pump.

105 The ring-like member 23 is prevented from rotating with the eccentric 24 due to the fixed pin 28 extending into the slot 26. This arrangement is such that it permits of the ring-like member 23 having the oscillatory movement previously described in connection with Figures 3, 4 and 5. Also it will be noted that the pin 28 (Figure 3) is disposed between the 110 openings 43 and 40 and has its periphery in contact with the wall of ring member 23 defining the chamber 22. Therefore, it necessarily follows that this pin 41 will serve as a seal to prevent the liquid entering the pump 115 from opening 40 from leaking into opening 43. That is to say, the pin 28 serves as a partition or barrier between the two openings 40 and 43. This means that the liquid entering 120 the chamber from the inlet 35 must travel 125 through the opening 43 to the outlet 36. 130

around with the ring 23 before it can be discharged into the opening 43 disposed in communication with the outlet 36.

Now, of course, it is to be understood that although I have illustrated and described in detail the preferred form of my invention, the invention is not to be thus limited, but only in so far as defined by the scope and spirit of the appended claims.

10 I claim as my invention:

1. In combination, in a rotary pump, a pump body including a cylinder having an annular opening comprising a pump chamber formed therein, an annular ring disposed in said chamber, an eccentric rotatable in said ring and adapted to impart an oscillatory motion to said ring, said ring having a slot formed in its periphery, and a pin fitted in said slot and rigidly connected to said cylinder, said ring being adapted to pivot on said pin during its movement by said eccentric.

2. In combination, in a rotary pump, a pump body including a cylinder having an annular opening comprising a pump chamber formed therein, an annular ring disposed in said chamber, an eccentric rotatable in said ring and adapted to impart an oscillatory motion to said ring, said ring having a slot formed in its periphery, a pin fitted in said slot and rigidly connected to said cylinder, said ring being adapted to pivot on said pin during its movement by said eccentric, an inlet connected to said chamber on one side of said pin, and an outlet connected to said chamber on the other side of said pin, said

pin serving as a sealing barrier between said inlet and outlet to prevent leakage of fluid from the inlet to the outlet.

3. In combination, in a rotary pump, a pump body including a cylinder having an annular opening comprising a pump chamber formed therein, an annular ring disposed in said chamber, an eccentric rotatable in said ring and adapted to impart an oscillatory motion to said ring, said ring having a slot formed in its periphery, and a cylindrical pin fitted in said slot and connected to said cylinder, said ring being adapted to pivot on said pin during its movement by said eccentric, said slot being slightly larger in width than the diameter of said pin, whereby said ring can move to and from said pin.

4. In combination in a rotary pump, a pump body including a cylinder having an annular opening comprising a pump chamber formed therein, an annular ring disposed in said chamber, an eccentric rotatable in said ring and adapted to impart an oscillatory motion to said ring, said ring having a slot formed in its periphery, and circular means fitted in said slot and connected to said cylinder about which said ring is arranged to pivot during the movement of the ring by said eccentric without moving said means relative to said cylinder.

In testimony whereof I have hereunto subscribed my name at Chicago, Cook County, Illinois.

CHARLES L. RAYFIELD.
